TRACK SHUNTING APPARATUS

Paul P. Sosinski, Edgewood, Pa., assignor to The Union Switch & Signal Company, Swissvale, Pa., a corporation of Pennsylvania

Application May 16, 1934, Serial No. 725,926

15 Claims. (Cl. 246—41)

My invention relates to track shunting apparatus, and more particularly to apparatus for providing track circuit shunting by light weight rail vehicles.

5 I will describe a few forms of apparatus embodying my invention, and will then point out the novel features thereof in claims.

In the accompanying drawings, Fig. 1 is a diagrammatic view showing one form of apparatus embodying my invention. Figs. 2, 3 and 4 are diagrammatic views showing modified forms of the apparatus illustrated in Fig. 1, also embodying my invention.

Similar reference characters refer to similar parts in each of the several views.

Referring first to Fig. 1, I have shown two rails 1—1^a which make up a stretch of railway track divided by insulated joints to form a track section 2—3 having a source of current 4 connected across the rails at one end of the section, and a track relay 5 connected across the rails at the other end of the section. The remaining apparatus which is shown in this figure is carried on the rail vehicle or is a part of the vehicle itself.

25 On the vehicle is a source S which supplies current to a motor M which, in turn, furnishes the motive power for the alternating current generator G. Considering the left-hand portion of the figure, current from generator G is supplied to the primary winding 18 of transformer T, through the reactor X which limits the drain on generator G when a low resistance shunting path is established by the shunting apparatus. The reference characters 6, 7, 8 and 9 designate four 30 wheels of the vehicle, joined by the axles 10—11 and 12—13, to form two shunt paths between the rails 1—1^a. Mounted on the axle 10—11 and in electrical contact therewith, at a point approximately half-way between the wheels 6—7, is a 35 collector ring 14 with which a stationary brush 15 makes contact as the vehicle moves along the track. Mounted on the axle 12—13 is a similar collector ring 16 having a brush 17 bearing thereon.

40 When transformer T is energized, the secondary winding 19 causes rail film breakdown current to flow over two rail paths, as indicated by the arrows, which I shall conveniently term paths A and B. Path A may be traced from the positive terminal of winding 19, brush 17, collector ring 16, axle 12, wheel 8, rail portion A, wheel 6, axle 10, collector ring 14, and brush 15, to the negative terminal of winding 19. Path B includes winding 19, brush 17, collector ring 16, 45 axle 13, wheel 9, rail portion B, wheel 7, axle 11,

5 collector ring 14, and brush 15, to the winding 19. The energy delivered by winding 19 is sufficient to break down the high resistance rail film which may exist on the rail surface. When the film is broken down in both of the rail paths traced above, two low resistance shunting paths will exist between rails 1—1^a by way of the wheel pairs 6—7 and 8—9 and their associated axles. The axles 10—11 and 12—13 are insulated from the body of the vehicle in order to confine the film 10 breakdown current to the rail paths.

10 Due to the symmetry of the two rail paths A and B, and after the film has been broken down at each of the wheel pairs 6—7 and 8—9, the 15 division of the breakdown current will be substantially equal in the two paths. Under this condition, the indicating relay K will be energized, closing front contact 20 to energize an indicator lamp L, and at the same time opening back contact 21 to remove the shunt circuit which 20 includes resistor R from around the current-limiting reactor X. Thus, the reactor will be fully effective in limiting the current drawn from generator G at such times as both rail paths A and B are broken down. Indicating relay K is a two- 25 element relay having the windings 23 and 24 which are energized from transformer windings 25 and 26, respectively. These transformer windings are wound on cores 27 and 28, respectively, which encircle the axle portions 10 and 11. The 30 current from generator G, in passing through the axle portions 10 and 11, causes a flux to be set up in each of the cores 27 and 28 whereby currents are induced in the windings 25 and 26 35 in accordance with the well known axle transformer principle. Resistor 29 is connected in series with winding 24 to obtain proper split-phasing of the currents in the two windings of relay K. Relay K is so designed as to pick up only when the breakdown currents in paths A 40 and B, and consequently in axle portions 10 and 11, are of normal magnitude and are approximately equal; and to release when a predetermined decrease in one or the other or both of 45 these two currents occurs.

In order to insure that a rail film breakdown potential will be maintained in both rail paths A and B and that the current division between these two paths will be approximately equal, I have provided two axle transformers BT and 50 BT^a which I shall term balancing transformers. These two transformers are substantially alike in characteristics, and the output windings 30 and 31 are so connected with each other that normally, when the currents in the axle portions 10 55

and 11 are equal, there is no interchange of current between the windings 30 and 31. If, however, the axle portion 10, for example, carries most of the current, indicating that path A is 5 broken down but path B is not, then the higher potential of winding 30 will overbalance the potential of winding 31, and ampere-turns will be supplied to transformer BT^a, in such a direction as to aid in establishing normal current flow in 10 axle portion 11. That is to say, the breakdown of one of the two rail paths does not result in the collapse of the breakdown voltage in the other path. Consequently, voltage will normally be 15 effective to maintain both paths broken down, thus establishing the two low resistance axle shunting paths from one to the other rail of the track.

If desired, windings 25 and 26 which energize relay K may be placed on the respective cores of 20 the balancing transformers BT and BT^a, thus eliminating the cores 27 and 28. Also, relay K may be made slow-acting to prevent response of the indicator L during a momentary loss of shunt. It is not essential that both transformers BT and 25 BT^a be placed on the same axle, provided one transformer responds to current in path A, and the other to current in path B.

The apparatus at the right-hand end of the car as viewed in the figure is identical with the 30 apparatus at the left-hand end which has just been described. The instantaneous polarities of the two secondary windings of transformers T and T¹, respectively, should be as indicated in the drawings, so that there will ordinarily be no 35 breakdown current flowing in the rail paths C and D. Conductor E is a low impedance cable which joins the mid-points of the secondary windings of transformers T and T¹. The purpose served by conductor E is to provide an auxiliary 40 shunting path which is particularly useful in case one of the rail paths A or B should fail to break down. For example, assuming that path B has failed to break down and that path A, and also 45 path B¹ at the right-hand end of the car, have been broken down, then a shunting path will 50 exist from rail portion A, by way of axle portions 10 and 12 and conductor E, to the rail portion B¹. It will be noted that should section 2-3 be provided with an alternating instead of 55 a direct current track circuit, the reactance potential drop due to the flow of track circuit current will be neutralized in the two halves of each of the windings 19 of transformers T and T¹, thus rendering the auxiliary shunting path through conductor E one of comparatively low 60 impedance. The use of conductor E is, of course, optional. When alternating current track circuits are used, the frequency of generator G should be sufficiently different from the track 65 circuit current frequency to prevent interference by the breakdown current with the operation of the signaling equipment.

Referring now to Fig. 2, the apparatus shown in this figure is practically the same as that shown in Fig. 1, with the exception that transformers T and T¹ of Fig. 1 have been combined into one 70 transformer T^a. Generator G¹ is a relatively low frequency, low voltage and high current generator, whereas generator G² is a relatively high frequency, high voltage and low current generator. The reason for using the two generators is to economize the energy of source S, which advantage is obtainable in this manner because the high breakdown current of generator G¹ is 75 supplied at very low voltage, the generator G²

furnishing the required break-down potential without appreciable current. Thus, the volt-ampere demand of the system is much lower than if one generator such as G of Fig. 1 is used.

The path of the breakdown current in Fig. 2 is indicated by the solid arrows and may be traced from the plus terminal of secondary winding 32 of transformer T^a, wire 33, brush 17, axle portion 12, wheel 8, rail portion A, wheel 6, axle portion 10, brush 15, wire 34, reactor X, secondary winding 35 of transformer T^a, wire 36, brush 37, axle portion 38, wheel 39, rail portion A¹, wheel 40, axle portion 41, brush 42, and reactor X¹, to the minus terminal of winding 32. It will be noted that windings 32 and 35 are series- 15 aiding in this path. At brushes 17 and 37, in the path traced above, in addition to the paths through rail portions A and A¹ of the upper rail 1, there branch out also the parallel paths through portions B and B¹ of the lower rail 1^a, 20 as indicated by the solid arrows. Therefore, due to the potential of windings 32 and 35 and the action of the balancing transformers BT, BT^a, BT¹ and BT^{1a}, the resistance film will be broken down at all eight of the car wheels illustrated, 25 whereby four axle shunting paths will be available, as in Fig. 1.

Winding 32 will also tend to cause current to flow in the path indicated by the dotted arrows, and which includes 12, 8, C, 40, and 41, for the 30 upper rail; as well as in the parallel path for the lower rail which includes 13, 9, D, 43, and 44. Similarly, winding 35 will tend to cause current to flow in the path which includes 38, 39, A¹, C, A, 6, and 10; and also in the parallel path which 35 includes 45, 46, B¹, D, B, 1, and 11. It will be noted that the currents in rail portions C and D tend to neutralize each other, so that the flow of the breakdown current will be chiefly confined to the rail portions A, B, A¹, and B¹, included in 40 the four axle paths 12, 8, A, 6, 10; 13, 9, B, 1, 11; 38, A¹, 40, 41; and 45, 46, B¹, 43 and 44, respectively.

Connected in series with primary winding 48, which is energized from generator G², is a condenser 47. This condenser offers low impedance to the high frequency current from generator G², but offers high impedance to the low frequency current from generator G¹, thus preventing the circuit of winding 48 from drawing an 50 appreciable amount of current from the other primary winding 49. If the power-saving feature is deemed to be unimportant, generator G² and winding 48 can be eliminated, provided the voltage of winding 49 is suitably increased. 55

If desired, instead of connecting winding 32 across the pair of inner axles, and connecting winding 35 across the outer axle pair, the connections of these windings with the left-hand or right-hand axle group can be interchanged, so 60 that the windings will then be connected between an axle of the inner pair and an axle of the outer pair. Also, a low impedance conductor 75 can be used for joining the mid-points of windings 32 and 35 to provide an additional shunting path, in the manner of conductor E of Fig. 1.

Referring now to Fig. 3, the arrangement shown therein combines certain of the features of the apparatus of Figs. 1 and 2. In Fig. 3, the balancing transformers are not used, dependence 70 being placed on the high frequency generator G² for maintaining a sufficiently high breakdown potential to insure a breakdown in both pairs of rail paths A, B; and A¹, B¹.

Winding 19 of transformer T furnishes the 75

breakdown current for the path 12, 8, A, 6, and 10, as well as for the parallel path 13, 9, B, 7, and 11. Similarly, the corresponding winding 19 of transformer T¹ furnishes the breakdown current for the two parallel paths 41, 40, A¹, 39, 38; and 44, 43, B¹, 46, and 45. The high frequency breakdown potential is applied across the mid-points of the two windings 19, by means of a low resistance secondary winding 50 of transformer T^b, and wires 51 and 52. Since the high frequency current flows in opposite directions in the two halves of each secondary winding 19, the impedance of these windings to the flow of this current is substantially neutralized. Under normal conditions, the high frequency current will flow in each of the following four rail paths: 10, 6, A, C, A¹, 39, 38; 12, 8, C, 40, 41; 11, 7, B, D, B¹, 46, 45; and 13, 9, D, 43 and 44.

Once the rail film is broken down by the potential of transformer T^b, the current which flows from transformers T and T¹ will provide four low resistance axle shunting paths from rail 1 to rail 1^a, as in Figs. 1 and 2. An auxiliary shunting path will also exist by way of wire 51, winding 50, and wire 52, in the same manner as previously described in connection with conductor E of Fig. 1.

Referring now to Fig. 4, I have shown one manner in which my invention can be applied to a car of the rubber-tired type, for example. In Fig. 4, the rail brush pairs 55-56 and 59-60, joined by cables 53, 54, and 57, 58, respectively, replace the left-hand wheel and axle pair of the previous figures insofar as shunting purposes are concerned. In a similar manner, two brush pairs, each joined by a shunting cable, take the place of the right-hand wheel and axle group.

The rails of track section 2¹-3¹ are supplied with alternating signaling current from a source BX-CX, by means of a track transformer 62, for the purpose of energizing the alternating current track relay 61. The frequency of the source G on the car is sufficiently different from the frequency of the wayside source BX-CX to prevent false operation of the track relay. Windings 25 and 26 which energize the indication relay K are shown wound directly on the cores of the respective balancing transformers BT and BT^a, although separate cores, as in Figs. 1 and 2, may be used. The single transformer T^c furnishes the breakdown current for the shunting equipment at both ends of the car. Secondary winding 63 of transformer T^c furnishes the breakdown energy for the path which includes reactor X, wire 57, brush 59, rail portion A, brush 55, wire 53, and wire 64. This winding also energizes the parallel path 58, 60, B, 56, and 54. Similarly, winding 65 of transformer T^c energizes the two paths 66, 67, A¹, 68, 69; and 70, 71, B¹, 72, 73. The mid-points of windings 63 and 65 are joined by a heavy conductor 74 which perform a similar function to that performed by conductor E of Fig. 1.

Conductors 53 and 54 which comprise a part of the one-turn primary winding for transformers BT and BT^a can be looped around the cores of the respective transformers for the purpose of forming a primary winding of a number of turns, if desired. The number of turns which can be used is determined, in part, by the amount of impedance to signaling current which can be safely inserted in the shunting path from brush 55 to brush 56. Since the path from brush 59 to brush 60 is practically free of impedance, some impedance can be tolerated in the former path.

It will be readily understood that the apparatus illustrated in Figs. 1, 2 and 3 is not limited to steel-wheeled vehicles, as this apparatus may be applied, as well, to rubber-tired vehicles by substituting the shunting cables of Fig. 4 for the wheel and axle groups of the first three figures. Also, in any of the embodiments of my invention illustrated in the drawings, the track circuit source of energy may be either direct or alternating current.

I do not claim as my invention the means for increasing the voltage applied to the breakdown circuit or for increasing the short circuit current therein, as such inventions are disclosed and claimed in the copending applications, Serial No. 15 629,030, filed August 16, 1932, by Howard A. Thompson, and Serial No. 678,629, filed July 1, 1933, by Bernard E. O'Hagan, respectively. Also, I do not claim as my invention the use of two sources, one of high potential and low current 20 capacity and the other of low potential and high current capacity for maintaining a low resistance track shunting path without an excessive expenditure of energy, as such invention is disclosed and claimed in the copending application Serial 25 No. 650,300, filed January 5, 1933, by Charles W. Butler and Bernard E. O'Hagan.

Although I have herein shown and described only a few forms of apparatus embodying my invention, it is understood that various changes 30 and modifications may be made therein within the scope of the appended claims without departing from the spirit and scope of my invention.

Having thus described my invention, what I 35 claim is:

1. In combination with a section of railway track and a rail vehicle thereon, two track shunts for said track, each including a pair of running wheels of the vehicle and an axle electrically insulated from the vehicle body, a source of current on the vehicle, two rail film breakdown paths one of which includes said source and one half of each of said two track shunts with the rail portion therebetween, and the other of which includes said source and the remaining half of each of said two track shunts with the rail portion therebetween, and means effective when the film breakdown current in said one path decreases below the value of the current in said other path 50 for increasing the breakdown current in said one path.

2. In combination with a section of railway track and a rail vehicle thereon, two track shunts for said track, each including a pair of running 55 wheels of the vehicle and an axle electrically insulated from the vehicle body, a source of current on the vehicle, two rail film breakdown paths one of which includes said source and one half of each of said two track shunts with the rail portion therebetween, and the other of which includes said source and the remaining half of each of said two track shunts with the rail portion therebetween, and means effective when the film breakdown current in either of said two 65 paths decreases below the value of the current in the remaining path for increasing the breakdown current in the lower current path.

3. In combination with a section of railway track and a rail vehicle thereon, two track shunts 70 for said track, each including a pair of running wheels of the vehicle and an axle electrically insulated from the vehicle body, a source of current on the vehicle, two rail film breakdown paths one of which includes said source and a 75

- portion of each of said two track shunts with the rail portion therebetween, and the other of which includes said source and the remaining portion of each of said two track shunts with the rail portion therebetween, and means effective when the film breakdown currents in said two paths become unbalanced for restoring a balance between said currents.
4. In combination with a section of railway track and a rail vehicle thereon, two track shunts for said track, each including a pair of running wheels of the vehicle and an axle electrically insulated from the vehicle body, a source of current on the vehicle, two rail film breakdown paths one of which includes said source and a portion of each of said two track shunts with the rail portion therebetween, and the other of which includes said source and the remaining portion of each of said two track shunts with the rail portion therebetween, means effective when the film breakdown currents in said two paths become unbalanced for restoring a balance between said currents, and an indicator for providing an indication when the currents in said two paths are balanced.
5. In combination with a section of railway track and a rail vehicle thereon, two track shunts for said track, each including a pair of running wheels of the vehicle and an axle electrically insulated from the vehicle body, a source of varying current on the vehicle, two rail film breakdown paths one of which includes said source and a portion of each of said two track shunts with the rail portion therebetween, and the other of which includes said source and the remaining portion of each of said two track shunts with the rail portion therebetween, and two balancing transformers one for each of said two paths, said transformers being energized from the breakdown current in the respective path and having their output windings connected together in such manner as to aid in maintaining a balance between the breakdown currents in said two paths.
6. In combination with a section of railway track and a rail vehicle thereon, two track shunts for said track, each including a pair of running wheels of the vehicle and an axle electrically insulated from the vehicle body, a source of varying current on the vehicle, two rail film breakdown paths one of which includes said source and a portion of each of said two axle shunts with the rail portion therebetween, and the other of which includes said source and the remaining portion of each of said two axle shunts with the rail portion therebetween, and two axle transformers one for each of said two paths, said transformers being energized by the axle current flowing in the respective path and having their output windings connected together in such manner as to aid in maintaining a balance between the breakdown currents in said two paths.
7. In combination with a section of railway track and a rail vehicle thereon, two axle shunts for said track, each including a pair of running wheels of the vehicle and an axle electrically insulated from the vehicle body, a source of varying current on the vehicle, two rail film breakdown paths one of which includes said source and a portion of each of said two axle shunts with the rail portion therebetween, and the other of which includes said source and the remaining portion of each of said two axle shunts with the rail portion therebetween, two axle transformers one for each of said two paths, said transformers being energized by the axle current flowing in the respective path and having their output windings connected together in such manner as to aid in maintaining a balance between the breakdown currents in said two paths.
8. In combination with a section of railway track and a rail vehicle thereon, a first pair of track shunts at one end of the vehicle, a second pair of track shunts at the other end of the vehicle, a source of current on the vehicle, a first winding energized from said source, two rail film breakdown paths one of which includes said first winding and a portion of each of the two track shunts comprising said first pair as well as the rail portion therebetween, and the other of which includes said first winding and the remaining portion of each of the two track shunts comprising said first pair as well as the rail portion therebetween, a second winding energized from said source, two additional rail film breakdown paths one of which includes said second winding and a portion of each of the two track shunts comprising said second pair as well as the rail portion therebetween, and the other of which includes said second winding and the remaining portion of each of the two track shunts comprising said second pair as well as the rail portion therebetween, and a low impedance connection joining the mid-points of said first and second windings for providing an auxiliary shunting path from one to the other rail of said track.
9. In combination with a section of railway track and a rail vehicle thereon, four spaced track shunts on the vehicle connected from one to the other rail of said track, a first source of film breakdown current on the vehicle, a first breakdown circuit joining two of said track shunts and including said first source, a second source of film breakdown current on the vehicle, a second breakdown circuit joining the remaining two of said track shunts and including said second source, the relative polarities of said two sources being arranged in such manner that current from said two sources will flow in the rail portions included between the spaced shunts which comprise end pairs of said track shunts but will be substantially neutralized in the intervening rail portions, thereby lowering the impedance of said first and second circuits to the flow of breakdown current from said two sources.
10. In combination with a section of railway track and a rail vehicle thereon, four spaced track shunts on the vehicle connected from one to the other rail of said track, a source of film breakdown current on the vehicle, a first winding energized from said source and joining two of said track shunts for impressing a breakdown potential across the rail portions included between said two track shunts, a second winding energized from said source and joining the remaining two of said track shunts for impressing a breakdown potential across the rail portions included between said two remaining track shunts, and a low impedance connection joining said first and second windings for providing an auxiliary shunting path from one to the other rail of said track.
11. In combination with a section of railway track and a rail vehicle thereon, four spaced track shunts on the vehicle connected from one to the other rail of said track, a source of film breakdown current on the vehicle, a transformer having a primary winding energized from said source and having two secondary windings, a first circuit

- joining two of said track shunts and including of said track shunts and including the other of said secondary windings, and a second circuit joining the remaining two of said track shunts and including the other of said secondary windings, the polarities of said two secondary windings being arranged in such manner that the breakdown current supplied by said secondary windings will flow in the rail portions included between the spaced shunts which comprise end pairs of said track shunts but will tend to be neutralized in the two intervening rail portions.
12. In combination with a section of railway track and a rail vehicle thereon, four spaced track shunts on the vehicle connected from one to the other rail of said track, a source of film breakdown current on the vehicle, a transformer having a primary winding energized from said source and having two secondary windings, a first circuit joining two of said track shunts and including one of said secondary windings, and a second circuit joining the remaining two of said track shunts and including the other of said secondary windings, and a low impedance connection joining the mid-points of said two secondary windings for providing an auxiliary shunting path from one to the other rail of said track.
13. In combination with a section of railway track and a rail vehicle thereon, four spaced track shunts on the vehicle connected from one to the other rail of said track, a first low frequency source of high current and low voltage on the vehicle, a second high frequency source of high voltage and low current on the vehicle, a transformer having a first and a second primary winding energized from said first and second sources respectively and having two secondary windings, a first circuit joining two of said track shunts and including one of said secondary windings, and a second circuit joining the remaining two of said track shunts and including the other of said secondary windings, the polarities of said two secondary windings being arranged in such manner that the breakdown current supplied by said secondary windings will flow in the rail portions included between the spaced shunts which comprise end pairs of said track shunts but will tend to be neutralized in the two intervening rail portions.
14. In combination with a section of railway track and a rail vehicle thereon, four spaced track shunts on the vehicle connected from one to the other rail of said track, a first low frequency source of high current and low voltage on the vehicle, a second high frequency source of high voltage and low current on the vehicle, a first and a second winding each energized from said first source, a third winding energized from said second source, a first circuit joining two of said track shunts and including said first winding, a second circuit joining the remaining two of said track shunts and including said second winding, and a circuit joining the mid-points of said first and second windings and including said third winding.
15. In combination with a section of railway track and a rail vehicle thereon, four spaced track shunts on the vehicle connected from one to the other rail of said track, a first low frequency source of high current and low voltage on the vehicle, a second high frequency source of high voltage and low current on the vehicle, a first and a second transformer each having a primary winding energized from said first source, a third transformer having a primary winding energized from said second source, a first circuit joining two of said track shunts and including the secondary winding of said first transformer, a second circuit joining the remaining two of said track shunts and including the secondary winding of said second transformer, and a circuit joining the mid-points of said two secondary windings and including the secondary winding of said third transformer.

PAUL P. SOSINSKI.
